THOMAS K. LESLIE, OF NEW YORK, N. Y.

DESIGN FOR A LABEL.

Specification forming part of Design No. 5,745, dated April 2, 1872.

Specification describing a Design for Printed Labels, invented by THOMAS K. LESLIE, of the city, county, and State of New York.

The nature of my design is fully represented in the accompanying photographic illustration, and consists in providing an ornamental design which may be used for a variety of labels, but especially for gloves, in which the various names of the dealers and the articles to be sold may be inserted in the ribbon or small spaces left blank in the photograph.

In this design the central figure is intended to represent a correct likeness of Alexandra, the Princess of Wales. At each end of the label are representations of medals; at the top is "Mary and her little lamb," resting in an easy and social position upon a bracket, which is partly concealed by the upper ribbon or blank space, in which the dealer's name or firm name may be inserted. The lower portion of said bracket projects out over the head of the central figure, with points projecting downward and elaborately ornamented, and immediately underneath its points the ribbons are laid that are formed in scrolls on each side of the central figure, in or on which the names of the articles to be sold may be printed, and between and around these several spaces flowers are intertwined, as shown in the photograph. At each lower corner a winged figure supports the medallions at each end; a boy and girl are represented in a sitting position near the lower portions of the frame that surround the likeness of the Princess in the center of the design; each holds a rod that incline toward each other at their upper ends and which appear to be supports to the central figure or the frame that surrounds it. The medallions have both been and are now used as trade-marks on gloves, and as this design will be chiefly used for such articles, it is considered appropriate to introduce them herein. The blank space at the bottom on the base of the design may be used for the address of the dealers.

Being a printer, my object is to provide a beautiful design for labels to such persons as may be able to make it appropriate to their business, and apply to me for printing.

I therefore claim as my invention—

A design for printed labels, consisting of the combination of the central likeness of the Princess, the two medals or medallions, and the other figures, interspersed with the ribbons and flowers, substantially in the manner above described and shown.

THOMAS K. LESLIE.
